J. A. GERSTENFELD

TIME SWITCH

Filed July 5, 1923

UNITED STATES PATENT OFFICE.

JESSE A. GERSTENFIELD, OF NEW YORK, N. Y., ASSIGNOR TO EUREKA TOOL AND MACHINE CO., OF NEWARK, NEW JERSEY.

TIME SWITCH.

Application filed July 5, 1923. Serial No. 649,587.

This invention relates generally to time switches and particularly to time controlled devices for operating standard electric switches.

5 One of the objects of my invention is to provide a time controlled device independent of an electric or other switch and adapted to be associated with and to operate such switch.

10 Another object of my invention is to provide within such device a spring controlled operating member adapted to actuate an independent switch device.

Another object of my invention is to provide in combination with such operating member a cocking element adapted to retain said member in cocked or inoperative position relative to a switch device, until said cocking element is caused to release such operating member.

Another object of my invention is to provide in combination with a switch operating member, equipped with a cocking element, a time piece having an alarm mechanism, provided with winding means therefor, the latter adapted to release said cocking element.

Another object of my invention is to provide, the time piece equipped with an alarm mechanism, an alarm escape arrangement embodied in said time piece, and winding means for said alarm adapted to operate a switch actuating mechanism, a stop element associated with such winding means adapted to reach in the field of operation of said escape arrangement, whereby the latter is stopped in its operation, thereby stopping the operation of said winding means.

The foregoing and further objects will be more fully apparent from the following description and the accompanying drawings showing representative features of my disclosure and forming part of this specification, and in which:

Figure 1 is a cross sectional view through my device, shown attached over an electric switch.

Figure 2 is a detail view showing the switch operating member in a position when the electric switch has been operated.

50 Figure 3 is a plan view of my device in open condition.

Figure 4 is a detail view of the cocking element of my device.

Referring to the drawings, numeral 10 indicates a standard electric push button switch secured in the wall and having a front plate 11 and push buttons 12 and 13. Attached to the plate 11 of the switch there is provided a housing 14 of my switch operating mechanism.

Housing 14 is provided with a hinged front cover 15. The back of the housing is provided with an aperture 16 for permitting the switch buttons 12 and 13 to protrude therethrough.

Side-wise arranged relative to said opening 16 is a switch button operating lever 17 pivotally mounted at 18. That switch operating lever or actuating member 17 is of an L shape and is provided at its longer end 70 with a lug 19. Opposite this lug 19 there is provided on the rear plate of housing 14 another lug 20. Both of these lugs are adapted to serve as a seat for expansion spring 21 which has a tendency of keeping 75 actuating member 17 in the position shown in Figure 2.

The shorter arm 22 of member 17 has at the end of the L shaped lug an extension 23 which is adapted to press against push button 12 of electric switch 10.

In the body of the lower portion of actuating member 17 there is provided an aperture 24 through which protrudes toothed cocking element 25 which is normally pressed 85 upwards against the upper edge of aperture 24 by means of a coil spring 26.

When lever 17 is compressed as shown in Figure 1 the tooth of cocking element 25 prevents lever 17 from pressing upon push button 12 of switch 10.

In this cocked position of lever 17 extension 23 is superimposed relative to push button 12. This push button in the position shown in Figure 1 indicates that the current 90 is now passing through switch 10.

In the position shown in Figure 2 the current is switched off.

The moment cocking element 25 has been turned in a downward direction it releases switch actuating member 17 whereby the longer arm of said member is pushed in the

direction from the rear plate of the housing 14, and the L shaped leg of member 17 is moved against push button 12 whereby the latter is thrust into the switch 10, while 5 push button 13 is moved outwards as seen in Figure 2.

In the cover 15 of the housing there is secured in any convenient manner a time-piece 27 provided with an alarm mechanism 10 not shown, and an escape arrangement, the moving part of which is indicated at 28.

The alarm mechanism of the movement is provided with winding means indicated at 29 which latter has at its end a tooth or 15 thumb 30, which is adapted to release cocking member 25 when the alarm movement is operated at a given time.

Associated with the winding means 29 is a stop member 31, which also moves with 20 the winding means when the latter is operated.

The field of operation of this stop member 31 reaches into the field of operation of escape element 28 and when reaching 25 escape element 28 it stops the latter in its reciprocating motion, thereby also stopping the movement of the winding member 29. The provision of stop member 31 is particularly desirable for the reason that it not 30 only limits the unwinding function of the winding member 29, but at the same time saves the repeated winding thereof, for the purpose of releasing cocking element 25.

The arrangement of the time piece 27 is 35 not shown, since any conventional alarm clock movement may be associated with my device, provided it is equipped with a winding element for the alarm mechanism and a stop member for the aforementioned functions required by them.

Operation:

When it is desired to, for instance, turn out the light in a store at a certain hour at night, push button 13 is pressed into 45 switch 10, whereby push button 12 is pushed outwards, and presses with it the L shaped lug of switch actuating member 17, and depresses expansion spring 21.

When the upper edge of opening 24 has 50 reached beyond the field of operation of the toothed portion of cocking element 25, the latter snaps upwards and prevents the lower lever portion of actuating member 17 from assuming its position shown in Figure 2.

Now the alarm mechanism of the time piece is wound to the position shown in Figure 3 so that thumb 30 is in upward position.

Then the time piece is set to the desired 60 hour when the alarm mechanism is to function, thereafter the lid of the housing is closed. At the hour desired the pin 28 of the escape arrangement is caused to function and will be reciprocated within its 65 slot.

At the same time the escape movement will permit the winding member 29 to move in clockwise direction together with stop member 31.

Thumb 30 passes over the cocking element 70 25, presses down the latter thereby releasing switch actuating member 17 which presses with its L shaped leg against switch button 12.

Through this function the electric current is cut off within the switch.

Thumb 30 continues in its clockwise direction travelling until stop member 31 comes in the path of reciprocating member 28 of the escape movement. Said pin 28 80 is stopped by stop member 31, whereby also the winding means 29 is prevented from further turning.

My device while shown in connection with an electric push button switch may be applied to any other apparatus requiring a time controlled releasing movement and I therefore shall not be limited only to the application shown in the drawings. Its great advantage lies in the fact that it may 90 be attached to any existing device requiring such releasing functions and which is subjected to the regulations of the fire underwriters. It therefore may be applied to any push button switch which has been approved. 95

While I have shown a specific form of my invention applicable for switching off an electric push button switch, be it understood that the identical mechanism in duplicate may be applied for the use of switching on and switching off an electric push button switch.

Such arrangement is not shown in the drawings as the application of my invention for such purpose is obvious. Be it 105 understood, therefore, that not only changes and improvements, but also the multiple arrangement of my invention may be made without departing from the broad scope of my invention, for which I claim:

1. In a clock controlled push button switch, a time piece having an alarm winding member, arranged in near proximity to a pair of push buttons, a spring propelled 110 pivotal lever operating between said time piece and said push buttons and adapted to actuate one of them, a spring controlled detent or cocking member extending through said lever and adapted to normally hold the latter in cocked position, said detent projecting into the path of operation of said winding member.

2. In a clock controlled push button switch, a housing provided with a hinged portion, a time piece arranged in the latter and provided with an alarm winding member, a pair of push buttons extending through said housing towards said time piece, a spring propelled lever arranged 115 within the housing and adapted to actuate 1

one of the push buttons, a spring actuated
detent projecting through said lever and
adapted to normally keep said lever in in-
operative position, said detent extending in-
5 to the path of operation of said alarm wind-
ing member, the latter adapted to engage
said detent and depress it, thereby causing

the release of said lever, which latter, pro-
pelled by its spring will actuate the push
button.

10

Signed at New York, in the county of
New York and State of New York, this 2nd
day of June A. D. 1923.

JESSE A. GERSTENFELD.
